CUTTER CHAIN

Morris P. Holmes, Claremont, N. H., assignor to
Sullivan Machinery Company, a corporation of
Massachusetts

Application July 30, 1934, Serial No. 737,495

11 Claims. (CL. 262—33)

This invention relates to cutter chains, and more particularly has reference to improvements in cutter bits and bit holders of a cutter chain especially designed for use for mining purposes.

5 An object of this invention is to provide an improved cutter chain. Another object is to provide an improved cutter bit and bit holder for a cutter chain. A further object is to provide an improved mining machine cutter chain designed to use for kerf-forming purposes and having improved cutter bit and bit-holding means. Yet another object is to provide an improved reversible or double-ended cutter bit for use with such a cutter chain, the bit having a plurality 10 of cutting points of an improved design, and improved positioning and holding means for positioning the bit in the bit block and holding the bit in position in the block. These and other objects will, however, subsequently more fully appear.

In the accompanying drawing there are shown, for purposes of illustration, two forms which the invention may assume in practice.

In this drawing—

25 Fig. 1 is a side elevational view of one illustrative embodiment of the improved cutter chain.

Fig. 2 is a cross sectional view taken on line 2—2 of Fig. 1, with parts in elevation.

Fig. 3 is a plan view of the cutter chain shown 30 in Fig. 1.

Fig. 4 is a longitudinally extending, vertical sectional view taken substantially on line 4—4 of Fig. 3, with parts in elevation and with a portion broken away to facilitate illustration.

35 Fig. 5 is a perspective view of the improved cutter bit.

Fig. 6 is a detail sectional view taken on line 6—6 of Fig. 4.

Fig. 7 is a cross sectional view taken substantially on line 7—7 of Fig. 5.

Fig. 8 is a view similar to Fig. 4, showing a modified form of construction.

Fig. 9 is an end elevational view of the bit block and bit shown in Fig. 8.

45 In the illustrative embodiment of the invention shown in Figs. 1 to 7, inclusive, 1 indicates the bit block, a series of which are pivotally connected by pivot pins 2 directly together in end-to-end relation to form an endless chain, one 50 end 3 of each bit block overlapping the end of the adjacent bit block in the manner shown in Fig. 2. Formed as an integral portion of the bit block is a boss 4 arranged with its longitudinal axis parallel to the median line of the chain, 5 and this boss is traversed by a rectangular socket

5 for receiving a cutter bit, generally designated 6, of an improved design. A set screw 7 threaded within the bit block is engageable with the bit body for securing the bit within the bit block socket in a manner to be later described. In 5 this illustrative construction, the boss 4 is cylindrical and is supported by transverse end portions 8, 8 in spaced relation with respect to a ledge 9, the latter arranged with its outer surface in a horizontal plane parallel to a plane 10 including the axes of the pivot pins 2, 2, the parts being so formed as to provide an opening 10 traversing the block beneath the bit socket boss 4. The transverse supporting portions 8, 8 have integral, transversely extending fin portions 15 11, 11 which act as clearing means for clearing the cuttings from the kerf cut by the chain, and the ledge 9 cooperates with these clearing fins in removing the cuttings from the kerf. The ledge 9 is provided with end abutment surfaces 20 12, 12 which abuttingly engage corresponding surfaces on the adjacent bit blocks as the cutter chain travels in its guide, for instance, in a guideway formed about the margin of a plane cutter bar or other suitable guide support. The 25 bosses 4 are formed on the bit blocks in different locations on different blocks with respect to a median plane at right angles to planes including the pivot pin axes, and the sockets 5 traverse these bosses in different angularly related 30 planes so as to form a staggered arrangement of the cutter bits, in the manner shown in Fig. 2, of a width sufficient to cut a kerf to admit the chain and its cooperating guiding means.

The improved cutter bit comprises a body 13, 35 generally in the shape of a parallelogram in side elevation and rectangular in cross section, and which has cutting points 14 and 15 formed at its ends at the opposite sides of the bit body. The points of the cutting portions are formed by cutting away the body to provide rearwardly inclined cutting faces 16 and 17 obliquely disposed with respect to the major axis of the bit. The front and rear edges of the bit body are transversely grooved or cut away at 18 and 19 to provide abutments 20 and 21, and one of these abutments is engageable with the outer surface of the block to limit inward movement of the bit within its socket, while the other abutment underlies the inner end of the setscrew so that, even if the setscrew were slightly loose, the bit could not be inadvertently released from its socket. The cutting portions at the ends of the bit have converging side surfaces 22, 22 forming cutting points of generally triangular shape in cross section, as 55

shown in Fig. 6, thereby to provide a generally triangular shaped front cutting face, a design whereby an improved cutting action is attained even when the cutting point becomes slightly dull. When the bit is within its socket, the front and rear end faces of the bit body lie in parallel planes extending transversely of the bit block at right angles to a plane including the axes of the pivot pins. Viewed in side elevation, it will be noted that the cutting away of the bit as at 18 and 19 provides side surfaces lying in the sides of a parallelogram and which lie in parallel planes respectively including the cutting points 14 and 15.

15. In the modification shown in Figs. 8 and 9, the cutter bit 6 is identical to that disclosed in the form above described, but, in this instance, is associated with a different type of chain structure. The chain, in this form of the invention, comprises a series of end-abutting bit blocks 30 pivotally connected by pivot pins 31 to strap links 32. The bit block body is traversed by a bit socket 33 terminating at its inner end with an enlarged opening 34 traversing the bit block. The ends of 25 the bit block are provided with inclined abutment surfaces 35 which are adapted abuttingly to engage correspondingly shaped surfaces on the next adjacent bit blocks. The bit is held within the bit block socket by a setscrew 36 in the same manner as in the form of the invention above described; and otherwise this form of the invention is the same.

As a result of this invention, it will be noted that an improved cutter chain is provided, having improved cutter bit and bit-holding means whereby the bit is held within its bit block in an improved manner. It will further be noted that an improved cutter bit of the double-ended type is provided, having improved means for positioning the bit with respect to the bit block socket and for securing the bit within the bit block socket. It will also be evident that by providing the cutting portions of the bit with the particular shape of cutting face and cutting points disclosed, an improved cutting action is attained, while the wearing qualities of the bit are greatly increased. These and other uses and advantages of the improved cutter chain will be clearly apparent to those skilled in the art.

50. While in this application there are described two forms which the invention may assume in practice, it will be understood that these forms are shown for purposes of illustration and that the invention may be further modified and embodied in various other forms without departing from its spirit or the scope of the appended claims.

What I claim as new and desire to secure by Letters Patent is:

1. A double-ended, reversible cutter bit having 60 a narrow elongated body terminating in cutting portions at its opposite ends and provided, in side elevation, with end and side surfaces lying in the sides of a parallelogram, and rectangular in cross section, the cutting portions at the opposite ends of the bit body providing cutting points 65 at the opposite sides of the bit, and means formed on the opposite sides of the bit body viewed in side elevation, providing abutments respectively engageable with an outer surface of a bit block for limiting inward movement of the bit within a bit block socket and with means for holding the bit within a bit block socket.

2. A double-ended, reversible cutter bit having 70 a narrow elongated body terminating in cutting portions at its opposite ends and provided, in side

elevation, with end and side surfaces lying in the sides of a parallelogram, and rectangular in cross section, the cutting portions at the opposite ends of the bit body providing cutting points at the opposite sides of the bit, and means formed on the opposite side surfaces of the bit body viewed in side elevation, providing abutments respectively engageable with an outer surface of a bit block for limiting inward movement of the bit within a bit block socket and with means for holding the bit within a bit block socket, said latter abutment means preventing release of the bit from a bit block socket even when the bit holding means is slightly released.

3. In a cutter chain, a bit block having a bit 15 receiving socket, and a double-ended, reversible cutter bit of narrow elongated form receivable in said bit block socket, said bit having cutting portions at its opposite ends terminating in cutting points and also having sides lying in parallel 20 planes passing through said cutting points respectively, and means on the body of said bit between said cutting portions and engageable with the outer surface of the bit block for limiting inward movement of the bit within the bit block 25 socket, said limiting means being arranged on the bit body outside of the parallel planes including said sides of the bit and the cutting points of said cutting portions.

4. In a cutter chain, a bit block having a bit 30 receiving socket, and a double-ended, reversible cutter bit of narrow elongated form receivable in said bit block socket, said bit having cutting portions at its opposite ends terminating in cutting points and also having sides lying in parallel 35 planes passing through said cutting points respectively, and means on the body of said bit between said cutting portions and respectively engageable with the outer surface of the bit block for limiting inward movement of the bit within the bit block socket and with holding means for preventing release of the bit from the bit block socket even when the holding means is slightly released, said limiting means being arranged on the bit body outside of said parallel planes including said sides of the bit and the cutting points of said cutting portions.

5. A cutter chain comprising a bit block having a bit-receiving socket, a double-ended, reversible cutter bit insertable in said socket, said bit having a narrow elongated body terminating in cutting portions at its opposite ends and provided, in side elevation, with end and side surfaces lying in the sides of a parallelogram, and of rectangular cross section, means on said bit block engageable with one such side surface of the bit body for clamping the opposed side surface to one wall of the bit block socket, and means on the bit body engageable with the outer surface of the bit block for limiting movement of the bit upon insertion 60 thereof within the bit block socket.

6. A cutter chain comprising a bit block having a bit-receiving socket, a double-ended, reversible cutter bit insertable in said socket, said bit having a narrow elongated body terminating in cutting portions at its opposite ends and provided, in side elevation, with end and side surfaces lying in the sides of a parallelogram, and of rectangular cross section, means on said bit block engageable with one such side surface of the bit body 65 for clamping its opposed side surface to one wall of the bit block socket, means on the bit body engageable with said clamping means for preventing inadvertent release of the bit from its socket even when said clamping means is slightly re-

- leased, and means on said bit body engageable with an outer surface of the bit block for limiting movement of the bit upon insertion thereof within the bit block socket.
5. 7. A cutter bit having a narrow elongated body terminating in cutting portions at its opposite ends and provided, in side elevation, with end and side surfaces lying in the sides of a parallelogram, and of rectangular cross section, the cutting portions at its opposite ends providing cutting points at the opposite sides of the bit body and having plane cutting faces inclined with respect to the parallel side surfaces of the bit body, and means formed on said parallel sides of the bit body providing abutments respectively for limiting inward movement of the bit within a socket of a bit block and engaging means for holding the bit within a bit block socket.
8. A cutter chain comprising a bit block having a bit-receiving socket, a double-ended, reversible cutter bit insertable in said bit block socket, said bit having a body of narrow elongated form terminating in cutting portions at its opposite ends and provided with abutment means spaced longitudinally of the bit body, one abutment means adjacent each cutting portion of the bit, said bit being reversible end for end within said bit block socket, and said abutment means which are respectively the nearer to the then-active cutting portions selectively engaging an outer surface on the bit block for limiting insertive movement of the bit within said bit block socket when said bit is in either of its end for end positions within said socket.
30. 9. A cutter chain comprising a bit block having a bit-receiving socket, a double-ended, reversible cutter bit insertable in said bit block socket, said bit having a body of narrow elongated form terminating in cutting portions at its opposite ends and provided with abutment means spaced longitudinally of the bit body, one abutment means adjacent each cutting portion of the bit, said bit
- being reversible end for end within said bit block socket, and said abutment means which are respectively the nearer to the then-active cutting portions selectively engaging an outer surface on the bit block for limiting insertive movement of the bit within said bit block socket when said bit is in either of its end for end positions within said socket, and holding means engageable with the bit body for holding the bit within said bit block socket when said bit is in either of its end for end positions, said holding means engageable with the abutment means which are not acting to limit bit insertion respectively when said bit is in either of its end for end positions within said socket.
10. 10. A cutter chain comprising a bit block having a socket, a double-ended, reversible cutter bit insertable in said bit-receiving socket, said bit having a narrow elongated body terminating in cutting portions at its opposite ends and provided, in side elevation, with end and side surfaces lying in the sides of a rhomboid, means on said block engageable with one such side surface of the bit body for clamping the opposed side surface to one wall of the bit block socket, and means on the bit body engageable with an outer surface of the bit block for limiting insertive movement of the bit within the bit block socket.
15. 11. A double-ended, reversible cutter bit having a narrow elongated body terminating in cutting portions at its opposite ends and provided, in side elevation, with end and side surfaces lying in the sides of a rhomboid, the cutting portions at the opposite ends of the bit body providing cutting points at the opposite sides of the bit, and means formed on the opposite side surfaces of the bit body viewed in side elevation, providing abutments respectively engageable with an outer surface of a bit block for limiting insertive movement of the bit within a bit block socket and with means for holding the bit within a bit block socket.

MORRIS P. HOLMES.
